UNITED STATES PATENT OFFICE

CHARLES KEMP AND ERNEST KEMP, OF BLOOMFIELD, INDIANA

RENEWABLE ELECTRIC FUSE

Application filed July 3, 1931. Serial No. 548,635.

The invention relates to electrical apparatus, particularly to fuses for the protection of various types of installations, and has for its principal object the provision of 5 a novel type of fuse which may be described as renewable inasmuch as it embodies a plurality of fuse elements which may be successively and selectively brought into operative position as occasion may demand.

10 It is well known in the art that it is a common practice to provide in lighting and other installations, a fuse of some sort or other which is adapted to break the circuit in the event of an overload such for instance 15 as is caused by a short circuit. It is also well known that the ordinary type of fuse comprises an insulating body having a central contact and an outer contact formed as a ring member both of which are connected 20 by a piece of wire or other metal which is adapted to melt or fuse at a certain predetermined temperature produced when there is a short circuit in a line. Whenever the ordinary type of fuse is "blown" the circuit 25 is of course broken and it therefore becomes necessary to replace the blown fuse with a new one. As new ones are not always available and as each one costs a certain amount considerable annoyance results from this situation.

30 It is with the above fact in view that we have devised the present invention which has for its object the provision of a fuse plug which is adapted to replace one of the ordinary type and which is provided with a plurality of fusible elements adapted to be brought successively into the circuit as one or another burns out or is melted so that the circuit will be restored without its being necessary to insert a brand new fuse device 35 in the socket provided for the reception of such.

40 Another object of the invention is to provide a renewable fuse device which is adapted to be screwed into the ordinary socket and which embodies a rotary element carrying a plurality of fuses adapted to be brought successively into the circuit as one or another may melt or burn out, it being quite 45 clear that there is a great saving in the cost

of maintenance and a considerable saving in the cost of the fuse devices themselves inasmuch as one constructed in accordance with our invention is adapted to take the place of six or more of the ordinary variety. 55

Another object of the invention is to provide a device of this character which is provided with means whereby when the rotary element is turned to bring the successive used elements into position positive stop 60 means is provided which will operate to maintain the proper position to establish a circuit.

An additional object is to provide a device 65 of this character which is of such construction that when all of the fusible elements have become blown out or melted it is merely necessary to provide a new rotary member carrying the fuse elements, thereby additionally making a saving in the cost of up- 70 keep, it being moreover a feature that the rotary element cannot be removed until it has made a complete revolution, that is to say until all of the fuse elements carried by 75 it have been used.

An additional object is to provide a device 80 of this character which will be simple and inexpensive to make, easy to install, positive in action, efficient and durable in service and a general improvement in the art. 85

To the attainment of the foregoing and other objects and advantages, the invention preferably consists in the details of construction and the arrangement and combination of parts to be hereinafter more fully described 85 and claimed, and illustrated in the accompanying drawing in which:—

Figure 1 is a longitudinal sectional view 90 through a complete device constructed in accordance with our invention.

Figure 2 is a horizontal sectional view taken on the line 2—2 of Figure 1.

Figure 3 is a side elevation of the rotary member alone.

Figure 4 is a bottom plan view thereof. 95

Figure 5 is a longitudinal detail section taken through the rotary member alone.

Figure 6 is a fragmentary similar view showing the section taken where the retaining pin is located and 100

Figure 7 is a detail perspective view of the central contact member carried by the stationary casing.

Referring more particularly to the drawing we have shown the device as comprising a casing 10 formed of some suitable insulating material such as vulcanite, fiber or the like, this detail being immaterial, and which is of hollow form with a closed bottom, the lower portion being, moreover, constricted as indicated at 11. As a matter of fact it is probably preferable that this casing 10 be of molded material of any one of numerous well known types. Mounted upon the constricted lower end 11 of the casing is a metallic shell member 12 which is threaded and which is held in place as by means of indentations 13 any desired number of which may be provided. Embedded within one side of the casing 10 during the manufacture thereof is an elongated metallic strip 14 which has one end suitably secured to and electrically connected with the shell 12 and which has its other end laterally deflected and terminating in a contact 15 projecting into the interior of the casing 10. Located at a point preferably diametrically opposite the contact 15 is a pin 16 which extends through one side of the casing 10 and which is embedded therein for a purpose to be described. The stationary part of the device further includes a spring contact of substantially horizontally disposed U-shape indicated at 17 located within the bottom of the casing 10 and having one arm 18 lying against the closed bottom 19 thereof and secured thereto by means of a rivet 20, it being probably preferable that there be a metallic washer 21 interposed between the head of the rivet 20 and the bottom surface of the insulating material 19. The contact member 17 is, as stated above, of U-shape and its upper arm is formed with a socket 22 constituting a terminal, it being quite clear that the head of the rivet 20 is adapted to engage against and be electrically connected with the central contact of a conventional type of socket into which the metallic shell 12 is screwed. Rotatably mounted within the casing 10 is a spindle 23 formed of insulating material and having a reduced or substantially conical lower end 24 and a stem 25 at its upper end, the latter projecting through and being journaled within a disk 26 at the open upper end of the casing 10 and serving as a handle for a reason to be explained. The spindle member 23 carries a plurality of fuses 27 formed as metallic strips of suitable material radiating from a common center or hub 28 which is secured with respect to the spindle 23 as by a screw 29, the head of which is adapted to seat within the socket 22 of the contact 17 above described.

At its upper portion the spindle member

23 is formed with an annular groove 30 defining shoulders 31 and 32, the latter of which is provided with a plurality of notches 33 registering with the upper ends of the fuse members 27 which terminate in contacts 34 radiating from the spindle and embedded therein. Furthermore, the spindle member 23 is formed with an elongated slot 35 located between two of the contacts 34 and into which the retaining pin member 16 may pass when it is desired to remove the spindle 23 when all of the fuse members 27 thereon have been burned out or melted.

In the operation of the device, it will of course be observed that it is intended to be used in identically the same manner as an ordinary fuse plug, that is to say the metallic shell 12 is intended to be screwed into the usual socket, not shown in the present case, so that the central rivet head 20 will engage with the central contact of the socket. When this is done, it will of course be apparent that whatever circuit is involved will include the central contact 20, the contact member or spring contact 17, any one of the fuse members 27 and corresponding elements 34, and the member 15 which connects with the member 14. Suppose, for the sake of illustration, that one of the fuse elements 27 becomes burnt out, "blown" or melted, such as will naturally occur in the event of a short circuit in the line being protected, it is easily understood that whenever this occurs it is merely necessary for the operator to grasp the handle 25 of the projecting portion of the spindle 23 and rotate the latter so as to bring a different contact 34 and fuse member 27 into circuit with the contact 15. Obviously, all of the fuse members 27 are connected with the contacts 34 and it is quite clear that the latter are intended to be engageable selectively and successively by the contact 15 so that there will be a plurality of the fuse elements 27 disposable in the circuit.

An important feature to be noted is that the pin member 16 is adapted to engage the successive notches 33 in the lower wall of the groove 30 in the spindle member, the notches being arranged in alignment with the fuse elements 27 so that there will be no possibility of error in the bringing of the successive fuse elements 27 into the circuit. Naturally, when all of the fuse elements 27 have been blown or melted it is necessary that the spindle member 23 be replaced. This is a very simple proposition though it is intended that it be impossible for the spindle member to be replaced until it has made a full revolution whereupon it is quite clear that the pin member 16 may extend into the longitudinally extending groove 30 whereupon it is clear that the entire spindle member 23 together with the burnt out fuse elements 27 thereon and of course the contacts 34 may be with-

drawn, this entire assembly being then replaced by a new one.

From the foregoing description and a study of the drawings it will be apparent that we have thus provided a very simply constructed and easily operated device which will efficiently perform all of the functions for which it is intended and which will operate as a material improvement in the art of renewable fuses, particularly as regards the renewability of such devices. It is thought that the construction, operation, and advantages should be readily apparent to one skilled in the art without further explanation.

15 While we have shown and described the preferred embodiment of the invention, it should of course be understood that we reserve the right to make all such changes in the details of construction as well as in the arrangement and combination of parts as will not depart from the spirit of the invention or the scope of the subjoined claims.

Having thus described the invention, we claim:

25 1. A renewable fuse device comprising a casing of insulating material, a metallic threaded shell member on one end of said casing adapted to be screwed into a socket, a spring contact bearing secured within said end of the casing and having a projecting element adapted to engage the central contact of a socket, a contact member embedded in the wall of said casing and connected with said shell member, a spindle of insulating material rotatably mounted within the casing, and a plurality of fuse elements carried by said spindle and radiating from a common element rotatably engaged with said spring contact bearing and having their other ends terminating in lateral extensions cooperating with said contact member embedded in the wall of the casing.

2. A renewable fuse device comprising a casing of insulating material, a metallic threaded shell member on one end of said casing adapted to be screwed into a socket, a spring contact secured within said end of the casing formed with a bearing and having a projecting element adapted to engage the central contact of a socket, a contact member embedded in the wall of said casing and connected with said shell member, a spindle of insulating material rotatably mounted within the casing, and a plurality of fuse elements carried by said spindle and radiating from a common metallic element rotatably engaged within said bearing and having their other ends terminating in lateral extensions cooperating with said second named contact, and detent means projecting radially through the side of the casing and cooperating with notches in the interior of said spindle for maintaining the same in a selected rotatably adjusted position.

3. A renewable fuse device comprising a

casing of insulating material, a metallic threaded shell member on one end of said casing adapted to be screwed into a socket, a spring contact formed with a bearing secured within said end of the casing and having a projecting element adapted to engage the central contact of a socket, a contact member embedded in the wall of said casing and connected with said shell member, a spindle of insulating material rotatably mounted within the casing and carrying a metallic element engaged within said bearing, and a plurality of fuse elements carried by said spindle and radiating from said metallic element and in electrical contact therewith and having their other ends engageable with said contact embedded in the wall of the casing, a detent element carried by the side of the casing and projecting into the interior thereof, said spindle having a peripheral groove accommodating said detent element and provided at the bottom of the groove with a plurality of notches corresponding to said fuse elements and adapted to receive the detent element.

4. A renewable fuse device comprising a casing of insulating material, a metallic threaded shell member on one end of said casing adapted to be screwed into a socket, a spring contact secured within said end of the casing and having a projecting element adapted to engage the central contact of a socket, a contact member embedded in the wall of said casing and connected with said shell member, a spindle of insulating material rotatably mounted within the casing, and a plurality of fuse elements carried by said spindle and radiating from a common point rotatably engaged with said spring contact and having their other ends terminating in lateral extensions cooperating with said contact embedded in the wall of the casing, a detent element carried by the casing and projecting into the interior thereof, and said spindle having a peripheral groove accommodating said detent element and provided at one side with a plurality of notches corresponding to said fuse elements and adapted to receive the detent element, said spindle further having a longitudinal groove leading into said peripheral groove for receiving said detent element to permit withdrawal and replacement of the spindle.

5. A renewable fuse device comprising a casing of insulating material, a metallic threaded shell member on one end of said casing adapted to be screwed into a socket, a spring contact secured within said end of the casing and having a projecting element adapted to engage the central contact of a socket, a contact member embedded in the wall of said casing and connected with said shell member, a spindle of insulating material rotatably mounted within the casing, and a plurality of fuse elements carried by

- and spindle and radiating from a common point rotatably engaged with said spring contact and having their other ends terminating in lateral extensions cooperating with said second named contact, said spindle having a projecting portion extending beyond the casing and serving as a handle, and an apertured cover plate for the casing containing a bearing for said handle.
6. A renewable fuse device comprising a casing of insulating material, a threaded metallic shell on one end of said casing adapted to be screwed into a socket, a spring member secured within said end of the casing and having a projection adapted to engage the central contact of a socket, a contact member at one side of said casing on the interior thereof connected with said shell, a spindle of insulating material rotatably mounted within the casing, a plurality of fuse elements carried by said spindle and radiating from a common element rotatably engaged with said spring member and having their other ends engageable with said contact at the side of the casing, means carried by the side of said casing and normally engaging the spindle for restraining the same against longitudinal removal from the casing, and means on said spindle cooperable with said last named member for permitting removal of the spindle.
7. A renewable fuse device comprising a casing of insulating material, a threaded metallic shell on one end of said casing adapted to be screwed into a socket, a spring member secured within said end of the casing and having a projection adapted to engage the central contact of a socket, a contact member at one side of said casing on the interior thereof connected with said shell, a spindle of insulating material rotatably mounted within the casing, a plurality of fuse elements carried by said spindle and radiating from a common element rotatably engaged with said spring member and having their other ends engageable with said contact at the side of the casing, means carried by the side of said casing and normally extending into a peripheral groove in the spindle for preventing removal of the spindle from the casing, said spindle having a longitudinal groove adapted to be brought into registration with said last named means for permitting removal of the spindle from the casing.
8. A renewable fuse device comprising a casing of insulating material, a threaded metallic shell on one end of said casing adapted to be screwed into a socket, a spring member secured within said end of the casing and having a projection adapted to engage the central contact of a socket, a contact member at one side of said casing on the interior thereof connected with said shell, a spindle of insulating material rotatably mounted within the casing, a plurality of fuse elements carried by said spindle and radiating from a common

element rotatably engaged with said spring member and having their other ends engageable with said contact at the side of the casing, means carried by the side of said casing and normally extending into a peripheral groove in the spindle for preventing removal of the spindle from the casing, said spindle having a longitudinal groove adapted to be brought into registration with said last named means for permitting removal of the spindle from the casing, the groove having one wall formed with notches corresponding in number to the number of fuse elements and cooperating with said last named means for maintaining the spindle in a selected rotatably adjusted position.

In testimony whereof we affix our signatures.

CHARLES KEMP.
ERNEST KEMP.
